(57) **CLAIM**

The ornamental design for a video game controller, as shown and described.

DESCRIPTION

FIG. 1 is a top perspective view of a video game controller embodying my new design, according to one embodiment; FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and

FIG. 8 is a right side view thereof.

FIG. 9 is a bottom perspective view showing a second embodiment of the design, the only difference being the additional features shown in broken lines on the bottom surface of the video game controller, it being understood that all other solid line features are the same as those of the first embodiment; and,

FIG. 10 is a bottom view showing a second embodiment of the design, the only difference being the additional features shown in broken lines on the bottom surface of the video game controller, it being understood that all other solid line features are the same as those of the first embodiment. The broken lines illustrate portions of the video game controller that form no part of the claimed design.

1 Claim, 9 Drawing Sheets
